(57) **CLAIM**

The ornamental design for a mobile phone, as shown and described.

DESCRIPTION

FIG. 1 is a front view of a mobile phone, showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a back perspective view thereof; and,

FIG. 9 is an enlarged back perspective view thereof of the region indicated in FIG. 8.

The broken lines depict portions of the mobile phone that form no part of the claimed design. The dash-dash broken lines encircling a portion of the drawings in FIGS. 8 and 9 are included to show a partially enlarged view only and form no part of the claimed design.
